[57] **ABSTRACT**

[22] Filed: **Feb. 4, 1975**

Apparatus and method for extracting water from pulp and of providing a pressed block of pulp, said apparatus comprising a press chamber, opposed moisture permeable press elements at respective opposite ends of said chamber, feed means adapted to introduce a predetermined quantity of moisture containing material into the chamber, the press chamber being movable between a first position wherein the opposed moisture permeable elements are arranged in generally vertically spaced relationship, and a second position wherein the said elements are in generally horizontally spaced relationship, in which position the pressed block is discharged from the press chamber. The method includes the steps of constraining the pulp between the opposed moisture-permeable elements, pressing the pulp to extract moisture therefrom whilst the chamber is disposed horizontally, and ejecting the resultant pressed block from the chamber.

WATER EXTRACTION METHOD AND APPARATUS

The invention concerns water extraction methods, and apparatus for use in practising the same.

One of the problems encountered in waste disposal systems is the difficulty in handling and storing the pulped waste, particularly where this has a relatively high reclaim value, such as waste paper, a typical instance being used trading stamps which have to be pulped for security reasons and in connection with which normal baling or incineration is an unacceptable alternative.

These stamps, when pulped for destruction, still contain about 80 percent water by weight and a denser bulk with lower moisture content is desirable. It is convenient to reduce the pulp to blocks or bricks which can be easily handled and stacked neatly for storage.

Initial tests show it to be desirable to limit the thickness of the blocks so as to permit the removal of a reasonable amount of water, and a block size of 12 inches $\times$ 8 inches $\times$ 2 inches has been eventually settled on the dry weight of the block being about 4 lbs and the density of the block being about 50 percent better than that of conventional baled paper, the blocks being readily stackable on a standard 48 inch square pallet.

However, hitherto difficulty has been experienced in producing blocks to this specification.

The primary object of the present invention is to provide a method of and a means for pressing pulp into block form.

According to the present invention, a method of extracting water from pulp and of providing a pressed block of pulp includes the steps of charging a generally vertically disposed press chamber from above with moisture-containing pulp, constraining the pulp between opposed moisture permeable elements arranged at the top and bottom of the said chamber, rotating the press chamber from its generally vertical disposition into a generally horizontal disposition, pressing the pulp to extract moisture therefrom whilst the chamber is disposed horizontally, and ejecting the resultant pressed block from the chamber.

The constraining of the pulp between the opposed moisture permeable elements may be accompanied by an initial moisture extraction step.

The invention also includes apparatus for practising the method as aforesaid which comprises a press chamber, opposed moisture permeable elements at respective opposite ends of the said chamber, at least one such element being movably mounted for adjustment relative to the other element to vary the separation of the elements for providing access to the chamber in the direction of movement of the element and for compressing material positioned between the said elements, and feed means adapted to introduce a predetermined quantity of moisture-containing material into the chamber for support by that moisture-permeable element arranged in opposed disposition relative to the aforementioned such element, the said press chamber being movable between a first position wherein the opposed moisture-permeable elements are arranged in generally vertically spaced relationship, in which position the chamber is charged with moisture containing material, and a second position wherein the said elements are in generally horizontally spaced relationship,

in which position the pressed block is discharged from the chamber.

In a preferred arrangement both moisture permeable elements are movable in the axial direction of the press chamber, that element defining the bottom of the chamber in the vertical mode of the chamber being adapted to eject the pressed block from the chamber on completion of the pressing operation.

According to a preferred feature, the feed means 10 comprises a filling tray movably transversely of a feed chute and adapted to receive moisture containing material therefrom between a load position, wherein the said tray is aligned with the chute, and a discharge position, wherein the tray is aligned with the press 15 chamber.

According to a still further feature of the invention, a plurality of press chambers will be provided in side-by-side disposition there being respective moisture-permeable elements and feed means for each such press 20 chamber.

The invention will now be described further, by way of example only, with reference to the accompanying drawings illustrating one embodiment thereof and in which:

25 FIG. 1 is an end elevation, partly in section, of a multiple-position press means constructed in accordance with the present invention;

FIG. 2 is a front elevation of the apparatus shown in FIG. 1;

30 FIG. 3 is a plan view of the multiple position press means of FIGS. 1 and 2; and

FIG. 4 is a diagrammatic illustration, drawn to a larger scale, of a typical moisture-permeable element as used in the apparatus.

35 Referring now to the drawings, and particularly to FIGS. 1 to 3 thereof, apparatus for extracting moisture from moisture-containing materials, say paper pulp, comprises a plurality of press units 11 arranged in banks at opposite sides of a machine framework 12, the 40 said press-units 11 being connected with a common supply hopper 13, as will hereafter become apparent.

The press-units 11 are of a like kind and each consists of a sleeve-like press-chamber body 14 of generally rectangular transverse cross-section mounted for pivotal motion about a horizontal axis 15 under the control of a piston and cylinder means 16 coupled between a fixed point 17 on the machine framework 12 and a lug 18 mounted on the said body 14, the press-chamber body 14 having a press-chamber 19 therein, two press- 45 plates 20, 21 arranged in opposed disposition and movable axially of the press body under the control of respective piston and cylinder means 22, 23, and a feed means 24 including a feed tray 25 adapted to receive material to be pressed from a supply thereof and to 50 deliver the same to the press-chamber.

55 As shown in FIGS. 1 to 3 each press-unit 11 is initially arranged with the axis of the press-chamber 19 thereof arranged generally vertically, the press-plates 20, 21 being in vertically spaced opposed disposition and respectively defining the top and the bottom of the press-chamber. The upper press-plate 20, as seen in FIG. 1, is movable into or out of engagement with the top of the press-chamber body 14, whilst the lower press-plate 21 is movable axially of such body to compress material within the press-chamber 19 against the upper press-plate 20.

60 Each press-plate 20, 21 is of the form shown diagrammatically in FIG. 4, and comprises a hollow body

26 of a transverse cross-section to correspond with that of the press-chamber, the front face 26a of the plate being provided with apertures 27 therein for drainage purposes and being covered by a suitable filter element 28 secured to the body in any convenient manner. The apertures 27 are inclined such that with the unit 11 pivoted so that the axis of the filter chamber is generally horizontal the apertures are inclined downwardly and inwardly of the hollow body. A drainage opening 29 is provided at the bottom of the hollow body.

The feed means 24 for each unit comprises a generally vertical feed chute 30 extending downwardly from the common hopper 13, the feed tray 25 aforesaid which is movable to or from alignment with the chute 30 at the lower end thereof, a closure means 31 formed integrally with the tray and movable therewith to close the lower end of the chute as the tray is moved away from its position of alignment therewith, and a piston and cylinder arrangement 32 adapted to move the tray between its position of alignment with the chute 30 and a position of alignment with the press-chamber 19.

The tray 25 is open-bottomed and moves in contact with a fixed, horizontal support surface 33, the said surface extending to a position directly adjacent to the press-chamber body 14 and in horizontal alignment with the top of the press-chamber.

The transverse cross-sectional dimensions of the tray correspond to those of the lower end of the feed chute 30, which feed chute is of increasing cross-section towards its lower end, and the capacity of the tray is selected having regard to the volume of the press-chamber and to the size of the charge to be fed thereto.

The closure means 31 comprises a plate extending rearwardly from the tray and in horizontal alignment with the top thereof, the said plate having a cutting edge 34 at its forward extremity to preclude trapping of material under processing between the front lower edge of the chute 35 and the corresponding rear upper edge 36 of the tray. Alternatively, a cutting edge could be provided at the front lower edge of the chute.

The piston and cylinder means 32 is supported on the machine framework in horizontal disposition, partially underlying the plate defining the closure means 31 aforesaid, and the piston 37 thereof is secured to a lug 38 extending rearwardly from the back of the tray. Actuation of the piston and cylinder means 32 serves to move the tray 25 forwardly from its position of alignment with the lower end of the chute across the top of the press-chamber and into alignment therewith. As the tray moves forwardly beyond the front edge 39 of the support surface 33 the open bottom of the tray is put in communication with the press-chamber and the contents of the tray fall, under gravity, into the chamber, the flowability characteristics of the material under processing being such that there is no significant forward movement of the contents of the tray, and thus no continuing filling of the tray, as the material falls into the chamber.

A conveyor means 40 is provided in front of each of the banks of press-units 11, the said conveyor means 40 serving to receive blocks 41 ejected from the press-chamber and to transfer the same for collection and disposal. As will hereafter be made apparent, the conveyor means 40 is of generally open-work form to allow of the ready drainage of water falling thereon from the unit upon the pivoting thereof back to its vertical disposition.

The operation of the unit, and the method of the invention, is as follows:

With the relative disposition of parts shown in FIG. 1, and assuming the tray 25 to be filled with pulp, the piston and cylinder arrangement 32 connected with the tray is actuated to shift the tray from its position of register with the feed chute 30 into alignment with the press-chamber 19.

The uppermost press-plate 20 is retracted to provide for the movement of the tray across the top of the chamber, whilst the lowermost press-plate 21 is at the bottom of the chamber so as to form a closure thereto.

On retraction of the tray, the uppermost press-plate 20 is moved downwardly under the control of its piston and cylinder means 22 into engagement with the top of the press-chamber body 14, thus to close the chamber 19, and the unit 11 is pivoted forwardly, to the dotted position shown, by actuation of the piston and cylinder means 16. Actuation of the piston and cylinder means 23 of the lower press-plate 21 axially of the press-chamber 19 to compress the material therein. Expressed moisture passes through the filter elements 28 at the front faces of the press-plates to the interior of the hollow bodies 26 which define such plates, and drains from such bodies through the drainage openings 29 therein.

On completion of the pressing cycle the 'upper' press-plate 20 is retracted and the 'lower' press-plate 21 ejects the block 41 of compressed, dewatered pulp onto the conveyor.

The unit 11 is moved back to its generally vertical disposition after the block 41 has been moved along the conveyor 40 and out of register with the unit, any water draining from the faces of the press-plates during the pivoting motion thereof passing through the reticulate conveyor and thereby away from the pressed blocks. During the pressing operation the feed tray will have been recharged from the hopper, and the cycle of operation is repeated.

For convenience, each bank of press units is pivoted between vertical and horizontal positions by a respective common piston and cylinder means.

Similarly, all of the feed chutes connect with a common feed hopper 13. The feed hopper comprises an annular bottom plate 42 having an upstanding wall 43 about the periphery thereof, a rotatable cone-shaped core 44 to the hopper arranged coaxially with the bottom plate 42, and a plurality of paddles 45 secured to the core 44 and extending generally radially thereof.

The bottom plate 42 is apertured in register with the tops of the feed chutes, the apertures 46 being in two banks of four, to correspond to the banks of press-units.

The cone-shaped core 44 is mounted on suitable support means 47 for rotation about the axis of the cone, and a drive means 48 is provided to effect such rotation.

The paddles 45 are of cranked form, the upper region 45a being secured to the core and the lower, or blade region 45b extending across the trough to sweep the bottom thereof.

At its lower edge the blade region has nylon brushes, not shown, in contact with the bottom of the trough.

The invention is not restricted to the exact features of the embodiment described, since alternatives will readily present themselves to one skilled in the art. Thus, whilst the feed hopper arrangement hereinbefore described may be found satisfactory, in some cases we

may prefer to use an arrangement wherein the paddles are curved backwardly in relation to the direction of rotation of the core.

Whilst we have described the invention in connection with a multiple-chamber machine, a single chamber arrangement may be found adequate in some cases. If a multiple-chamber machine is required, then the chambers may be arranged other than in banks. If required, the units may be angularly spaced about a common centre and pivoted individually. The units may be operated in sequence, if desired.

We claim:

1. A method of extracting water from pulp and of providing a pressed block of pulp including the steps of charging a generally vertically disposed press-chamber from above with moisture-containing pulp, constraining the pulp between opposed moisture-permeable elements arranged at the top and bottom of the said chamber, rotating the press-chamber from its generally vertical disposition into a generally horizontal disposition, pressing the pulp to extract moisture therefrom whilst the chamber is disposed horizontally, and ejecting the resultant pressed block from the chamber.

2. The method as claimed in claim 1 including the further step of compressing the pulp when initially constraining the same, thereby to effect a preliminary extraction of moisture therefrom.

3. Apparatus for extracting water from pulp and of providing a pressed block of pulp, comprising a press-chamber, opposed moisture-permeable elements at respective opposite ends of the said chamber, at least one such element being movably mounted for adjustment relative to the other element to vary the separation of the elements for providing access to the chamber in the direction of movement of the element and for compressing material positioned between the said elements, and feed means adapted to introduce a predetermined quantity of moisture-containing material into the chamber for support by that moisture-permeable element arranged in opposed disposition relative to the aforementioned such element, the said press-chamber being movable between a first position wherein the opposed moisture-permeable elements are arranged in generally vertically spaced relationship, in which position the chamber is charged with moisture-containing material, and a second position wherein the said elements are in generally horizontally spaced relationship, in which position the pressed block is discharged from the chamber.

4. Apparatus as claimed in claim 3, wherein both moisture-permeable elements are movable in the axial direction the the press-chamber, that element defining the bottom of the chamber in the vertical mode of the chamber being adapted to eject the pressed block from the chamber on completion of the pressing operation.

5. Apparatus as claimed in claim 3, wherein the feed means comprises a filling tray movable transversely of a feed chute between a load position, wherein the said tray is aligned with the chute, and a discharge position, wherein the tray is aligned with the press-chamber, the said tray being adapted to receive moisture-containing material from the feed chute.

6. Apparatus as claimed in claim 5, wherein the tray further includes a closure means cooperable with the feed chute for sealing the same in the discharge position of the tray.

7. Apparatus as claimed in claim 6, wherein the plate has a cutting edge at its forward extremity cooperable with the lower edge of the chute.

8. Apparatus as claimed in claim 3, wherein the structure comprising the press-chamber and the moisture-permeable elements is pivotal about an axis extending transversely of the press-chamber for movement between the first and second positions.

9. Apparatus as claimed in claim 3, wherein each moisture-permeable element comprises a hollow body having an apertured front face thereto and a filter element extending across the said front face.

10. Apparatus as claimed in claim 9, wherein the apertures in the front face of the body are inwardly and downwardly inclined with respect to the hollow body when the press-chamber is arranged with its axis horizontal.

11. Apparatus as claimed in claim 3, further including a conveyor to which the pressed blocks are discharged.

12. Apparatus as claimed in claim 11, wherein the conveyor is of openwork form thereby to provide for the ready drainage of moisture therethrough.

13. Apparatus as claimed in claim 3 including a plurality of press-chambers and respective moisture-permeable elements and feed means therefor.

14. Apparatus as claimed in claim 13, including a common hopper to which the individual said feed means are connected.

15. Apparatus as claimed in claim 14 including a rotator arranged co-axially with and rotatable relative to the said hopper, the said rotator comprising a cone-shaped core and a plurality of paddles extending radially outwardly thereof, the said paddles being shaped and dimensioned to displace material lying on the floor of the hopper on rotation relative to the hopper.

16. Apparatus as claimed in claim 3, further including pressure fluid operated piston and cylinder means adapted for effecting movement of each movable moisture-permeable element.

17. Apparatus as claimed in claim 3, further including pressure fluid operated piston and cylinder means adapted for effecting movement of the or each press-chamber between first and second positions thereof.
